DESIGN FOR A TOILET SEAT HINGE

Harold D. Watson, Beloit, Wis., assignor to Falls Plastics Company, Sheboygan Falls, Wis., a corporation of Wisconsin

Application May 12, 1943, Serial No. 110,184

Term of patent 14 years

To all whom it may concern:

Be it known that I, Harold D. Watson, a citizen of the United States, residing at Beloit, in the county of Rock and State of Wisconsin, have invented a new, original, and ornamental Design for a Toilet Seat Hinge, of which the following is a specification, reference being had to the accompanying drawings, forming part thereof.

Figure 1 is a top plan view of a toilet seat hinge showing my new design;

Figure 2 is a view in front elevation thereof;

Figure 3 is a sectional view on the plane of the line 3—3 in Figure 1;

Figure 4 is a sectional view through Figure 2 on the plane of the line 4—4 in Figure 2.

Figure 5 is a perspective view of the hinge;

Figure 6 is a view in front elevation of the hinge with the cover hinge part raised; and

Figure 7 is an end view of the hinge.

I claim:

The ornamental design for a toilet seat hinge, as shown.

HAROLD D. WATSON.
